UNITED STATES PATENT OFFICE

ALFRED C. GILBERT, OF NORTH HAVEN, CONNECTICUT, ASSIGNOR TO THE A. C. GILBERT COMPANY, OF NEW HAVEN, CONNECTICUT, A CORPORATION OF MARYLAND

DESIGN FOR A CONSTRUCTION TOY ELEMENT

Application filed August 29, 1931. Serial No. 40,954. Term of patent 14 years.

To all whom it may concern:

Be it known that I, ALFRED C. GILBERT, a citizen of the United States, residing in North Haven, in the county of New Haven and State of Connecticut, have invented a new, original, and ornamental Design for a Construction Toy Element, of which the following is a specification when taken in connection with the accompanying drawings, of which—

Fig. 1 is a front elevation of a construction toy element showing my new design, and

Fig. 2 is an end view of the same.

I claim:

The ornamental design for a construction toy element substantially as shown.

ALFRED C. GILBERT.
